MACHINE FOR EVENING SURFACES OF ARTICLES

Filed June 7, 1926

Inventor
Oscar H. Brown
By his Attorney
Nelson M. Howard

UNITED STATES PATENT OFFICE

OSCAR H. BROWN, OF SALEM, MASSACHUSETTS, ASSIGNOR TO THE TURNER TANNING MACHINERY COMPANY, OF PORTLAND, MAINE, A CORPORATION OF MAINE

MACHINE FOR EVENING SURFACES OF ARTICLES

Application filed June 7, 1926. Serial No. 114,222.

The invention relates to machines for evening surfaces of articles in process of manufacture and is illustrated as embodied in a machine for evening the cylindrical surfaces of certain types of brushes especially adapted for use in tanning machinery.

In the manufacture of well-known types of brushes it is the common practice to assemble the bristles or other like material in bunches and then to insert the bunches individually in perforations or sockets in a backing member, means being provided for fastening each bunch of bristles within its socket in the backing member. Other means and ways of securing the bristles to a backing member are also employed, but in any case the ends of the bristles of such brushes extend outwardly from the backing member unequal distances so that at a certain stage in its manufacture there is no uniformity in the length of the bristles which compose the brush. In truing operations upon brushes, as heretofore performed, knives or cutters of various sorts and arrangements have been employed for the purpose of reducing the bristles to uniform length or imparting any other desired surface contour to the brushes. Much difficulty has been experienced in securing uniformity of cutting operations and in maintaining the cutters to the sharpness required for efficient operation.

Accordingly, it is an object of this invention to provide improved mechanism for evening, truing or otherwise imparting a predetermined desired contour to the surfaces of brushes or other articles. The invention is herein discussed with particular reference to its applicability to burning or singeing the ends of bristles or brushes, although it is to be understood that in various aspects the invention is not limited to burning or singeing the ends of bristles, nor to operation upon brushes, but may have various applications in the treatment of articles having bristly or napped surfaces, or surfaces having similar characteristics.

To these ends, and in accordance with important features of the invention, the illustrated machine is provided with brush supporting means, heated burning or singeing

means, and means for effecting relative movement of the brush supporting means and the singeing means to burn or singe the ends of the bristles of a brush in such a manner as to impart a predetermined desired contour to the operative surface of the brush. Preferably, and as shown, the singeing means comprises a coil of wire electrically heated to a white heat and adapted to be presented in contact with the ends of the bristles of a brush and moved relatively to the surface of the brush always at the same distance from the backing or surface in which the bristles are set so as to cause the bristles to be of uniform length. In order that the illustrated coil of wire may operate at its highest efficiency, it is rotated to bring successive portions of the coil in contact with the bristles, no one portion of the coil remaining in contact with the bristles long enough to be cooled thereby below the point of effectiveness as a singeing means.

Since in the operation of burning off or singeing the ends of the bristles there is danger of the spread of flames to adjacent portions of the brush, the illustrated machine is provided with simple and inexpensive means for preventing kindling of the brush, said means comprising a wiper plate located closely adjacent to the singeing coil and constructed and arranged to engage the freshly burned or singed bristles. By thus engaging the freshly-singed bristles, the wiper promptly puts out any flame, thus preventing any excess singeing of the bristles.

In the illustrated construction also, a frame or carriage is provided for supporting the coil of wire and a motor which furnishes the power for rotating the coil, the coil and the motor being supplied from the same source of electrical energy and both being controlled by the same switch so that upon closing the circuit the coil will be heated and the motor energized to rotate the coil. Since the illustrated mechanism is designed with especial reference to truing the cylindrical surfaces of relatively long brushes, the illustrated frame or carriage is mounted for movement lengthwise of a brush that is at the same time rotated so that the cylindrical surface

of the brush is progressively presented to the heated coil for the proper singeing of the bristles.

These and other features of the invention 5 and novel combinations of parts will now be described in detail with reference to the accompanying drawings.

In the drawings,

Fig. 1 is a view in side elevation and partly 10 in section showing one embodiment of the invention;

Fig. 2 is a view looking from the right in Fig. 1;

Fig. 3 is a diagrammatic representation of 15 the electrical connections to the motor and to the heating coil;

Fig. 4 is a detail view on a small scale showing the means for moving the tool carriage; and

20 Fig. 5 is a detail view of the carriage moving means looking from the left in Fig. 4.

In the illustrated machine there is provided a frame or carriage 6 for supporting means for truing the surfaces of cylindrical 25 brushes, the said means comprising, as shown, a coil 8 of wire of sufficient electrical resistance so that upon passage of current through it the coil will be heated to a white heat. For supporting the wire there is provided 30 a cylindrical member 10 which is composed of a material, such as lava, non-conducting with respect to electricity and, at the same time, highly refractory to heat. In order that the cylinder 10 and the coil 8 may be rotated 35 to present fresh heated surfaces on the coil to the bristles of the brush 11, (since a portion of the coil might be cooled too much for effective work if allowed to remain longer than a certain maximum time in contact with 40 a brush), the cylinder is mounted upon a shaft 12 carried by bearings 13 in the carriage 6. Mounted fixedly on the shaft 12 are contact rings 14, one on each side of the coil 8, to which the ends of the coil 8 are connected.

45 Pivoted at 16 to the frame or carriage 6 is a contact brush 18 pressed upon by a spring 20 so that the concaved end 22 of the contact brush is held yieldingly in contact with the adjacent ring 14, it being understood that a second contact brush 19 is provided in connection with its adjacent ring 14 and that each contact brush and spring 20 are insulated in their mountings upon the carriage 6. Extending from each contact brush is a 55 wire for carrying the electric current which heats the coil 8. In the construction shown a wire 22 (Figs. 1 and 3) leads from the contact brush 18 and connects with a binding post 24 at one end of a wire 26 whereas another wire 28 leads from the other contact brush 19 to a binding post 30 at the upper end of a wire 32, the latter having interposed between its ends a fuse 34 designed to 60 protect the coil 8 so that the latter will not burn out in case of short circuiting. Con-

nected to the binding post 24 is a wire 36 which leads to an electric motor 38 mounted upon a bracket 40 secured to the carriage 6. Intermediate between the ends of the wire 36 is a fuse 42 designed to protect the motor. In circuit with the motor is a second wire 44 which is connected to the wire 32, the wires 26 and 32 being connected by means of a switch 46 with wires 48 and 50, respectively, which lead in from line wires 52 from any suitable source of electric supply. It will be understood that proper manipulation of the switch 46 results in the desired control of both the motor 38 and the coil 8, closing of the switch resulting in energizing the motor to rotate the coil and, simultaneously therewith, heating the coil to make it effective to burn the ends of bristles of a brush in a truing operation upon the latter.

To prevent undesirable heat from being 55 transmitted from the coil 8 to the frame or carriage 6 and to the supports of the motor 38, there is provided a guard 55 which covers the back of the coil 8 and the front of the motor 38.

As illustrated, the means for connecting the motor 38 with the shaft 12 comprises a worm 60 sleeved fixedly upon the armature shaft 62 of the motor 38. Mounted in a bracket 64 attached to the carriage 6 is a shaft 66 having attached to its upper end a worm gear 68 positioned to mesh with the worm 60 to be driven thereby. At its lower end the shaft 66 carries a worm 70 positioned so as to be in mesh with a worm gear 72, shown most clearly in Fig. 2 of the drawings, the worm gear 72 being fixedly attached to the shaft 12. The illustrated gearing for the shaft 12 is designed to drive the latter at a speed of approximately 35 revolutions per 105 minute.

For the purpose of preventing kindling of the brush in the operation of singeing bristles, means is provided for operating upon the freshly burned or singed bristles to 110 prevent the spread of flames from the seat of operation to the adjacent portions of the brush. As illustrated, this means comprises a wiper plate 80 carried by brackets 82 extending downwardly from the frame or carriage 6, the wiper plate being mounted adjustably in the brackets so that its operative end 84 may be properly adjusted as occasion may require to wipe over the ends of treated bristles shortly after they have been singed or burned by the coil 8 to put out any flame on the recently singed bristles. Upon inspection of Fig. 2 it will be observed that the wiper plate 80 is considerably wider than the coil 8 so as to provide such a relatively broad path for its sweep over the bristles as to insure the extinguishing of any flame which starts at the seat of singeing. This wiper plate serves the function also of limiting the 120 burning of the bristles to that accomplished 125 130

at the point of singeing. Adjustment of the wiper can be made in accordance with the burning characteristics of the bristles to prevent excessive burning thereof.

5 To facilitate treating parts of a brush or similar article circumferentially of its periphery, in the illustrated machine, the brush 11 is mounted for rotation relatively to the coil 8 by means of a belt 87 in standards, one 10 of which is shown at 88 in Fig. 4. To provide for treating different parts lengthwise of the periphery of a brush or the like of substantial length, in order that the whole or as much 15 of the length of the work may be treated as desired, the carriage 6 is mounted for movement longitudinally of the brush 11 and the means for this purpose comprises a tool post 90 having a recess for the reception of a projecting portion 92 of the frame or carriage 6 20 which is secured within the recess by means of a screw threaded member 94, the tool post 90 comprising also a convexly surfaced member 96 seated within a cup 97 in a block 98 mounted in a T slot in a sliding carrier 100, 25 the arrangement being such that upon tightening the screw threaded member 94 the tool post 90, the member 96, the block 98, and the carriage 6 are all fixedly secured to the sliding carrier 100 (Fig. 4), guided by means 30 comprising co-operating recesses 102 and ribs 104, upon a lathe-like bed member 106. For moving the carrier 100 along the bed 106 the former is provided with an interiorly screw-threaded extension 108 through which passes 35 a screw 110, rotation of which causes travel of the carrier 100 first in one direction and then in the reverse direction by means (not shown) which may be such as are commonly employed for that purpose. For example, 40 the screw-shaft driving mechanism and reversing clutch means disclosed in United States Letters Patent No. 1,520,209, granted December 23, 1924, upon application of Lyndon O. Ramsdell, may be employed in connection with the screw 110 of the illustrated 45 machine.

In operating with the machine, a brush is first positioned within the standards, one of which is shown at 88 (Fig. 4) and the carriage 50 6 is properly adjusted within the tool post 90 so as to position the coil 8 at the proper distance from and at the proper height with respect to the center of rotation of the brush 11. The switch 46 is thrown to effect heating of 55 the coil 8 and to cause the motor 38 to rotate the coil. Beginning at one end of the brush the carriage 6 is caused to travel the whole length of the brush while the brush is rotated. The speed of rotation of the brush 11 and the 60 rate of longitudinal movement of the carriage 6 are so related that all parts of the cylindrical surface of the brush are properly singed to produce a brush with a trued or even surface.

65 Having described my invention, what I

claim as new and desire to be secured by Letters Patent is:—

1. A machine for imparting a predetermined contour to the surface of a brush comprising, brush supporting means, singeing means, and means for relatively moving the brush supporting means and the singeing means to present different portions of the periphery of the brush successively to the singeing means. 75

2. A machine for imparting a predetermined contour to an irregular napped surface or to a surface having bristles of various lengths comprising, work supporting means, singeing means, means for effecting relative movement between the work supporting means and the singeing means to present successive portions of the surface of the work to the singeing means, and means operative during the singeing operation for preventing excessive singeing of the bristles. 80

3. A machine for imparting a predetermined contour to the operating surface of a brush comprising, brush supporting means, heating means, means for rotating the heating means in contact with the brush, and means for effecting relative linear movement of the heating means and the brush supporting means. 85

4. A machine for singeing bristles held fixedly relatively to each other or the napped surfaces of articles comprising, heating means, article supporting means, means for effecting relative movement of the heating means and article supporting means to cause successive portions of the surface of an article to be singed, and a wiper projecting into the path of the bristles for preventing excessive burning of the bristles. 90

5. In a machine for burning the ends of bristles, a support for the bristles, heated means for burning the bristles, a mounting for the heated means, means for causing relative movement between the heated means and the support for the bristles during the burning operation and means for preventing excessive burning of the bristles. 95

6. In a machine for burning the ends of bristles, a movable support for the bristles, rotatably mounted heated means for burning the bristles, means for rotating the heated means to burn bristles brought into contact therewith, said bristles support and heated means being relatively movable during bristle burning operations, and a wiper for preventing excessive burning of the bristles during relative movement between the wiper and bristles. 115

7. In a machine for burning the ends of bristles, a support for the bristles, heated means for burning the bristles relatively movable with respect to the support, a member of material refractory to heat on which the heated means is mounted, and means for rotating the member and the heated means to 120

- present successively fresh heated surfaces for contact with the bristles during relative movement between the bristles support and the heated means.
5. In a machine for burning the ends of bristles of a brush, a cylinder of material refractory with respect to heat, a metal member mounted on the cylinder, a brush support adjacent to said cylinder, means for rotating the cylinder and the metal member thereon, means for heating the metal member while it is rotating in contact with the bristles, and means for preventing kindling of the brush.
10. In a machine for burning the ends of bristles, a support for the bristles, an electrically heated wire to burn the ends of bristles, means for causing relative movement between the wire and the support for the bristles to bring the latter progressively into contact with the heated wire, and a wiper plate located adjacent to the wire for preventing excess burning of the bristles.
15. In a machine for burning the ends of bristles, a support for the bristles, a coil of wire arranged to be electrically heated to burn the ends of bristles, means for causing relative movement between the coil of wire and the support for the bristles to bring the latter progressively into contact with the heated wire, and means for rotating the coil of wire on its axis during burning of the bristles.
20. In a machine for burning the ends of bristles, a support for the bristles, a coil of wire arranged to be electrically heated to burn the ends of bristles, means for causing relative movement between the coil of wire and the support for the bristles to bring the latter progressively into contact with the heated wire, and a wiper plate located adjacent to the wire for preventing excess burning of the bristles.
25. In a machine for burning the ends of bristles, a support for the bristles, a coil of wire arranged to be electrically heated to burn the ends of bristles, means for causing relative movement between the coil of wire and the support for the bristles to bring the latter progressively into contact with the heated wire, and means for rotating the coil of wire on its axis during burning of the bristles.
30. In a machine for burning the ends of bristles, a support for the bristles, a coil of wire arranged to be electrically heated to burn the ends of bristles, means for causing relative movement between the coil of wire and the support for the bristles to bring the latter progressively into contact with the heated wire, and means for rotating the coil of wire on its axis during burning of the bristles.
35. In a machine for burning the ends of bristles, a support for the bristles, a coil of wire, a rotatably mounted cylinder of non-conducting material refractory with respect to heat on which the wire is wound, means for rotating the cylinder and the coil of wire wound thereon, and means for passing a current of electricity through the coil to heat the same while it is rotating, the support for the bristles and the coil of wire being relatively movable in a linear direction during the burning of bristles.
40. In a machine for burning the ends of bristles, a support for the bristles, a coil of wire arranged to be electrically heated, a shaft upon which the coil is mounted, means for driving the shaft so that fresh heated surfaces of the coil are presented successively to the bristles, and means for conducting electricity to the coil during the rotation of the latter, the support for the bristles and the coil of wire being relatively movable in a linear direction during the burning of bristles.
45. In a machine for burning the ends of bristles, a support for the bristles, a coil of wire arranged to be electrically heated, a cylinder of non-conducting material for supporting the coil of wire, a shaft to which the cylinder is connected, means for rotating the shaft and the coil carried thereby, and means for supplying electricity to the rotating coil of wire, the support for the
- bristles and the coil of wire being relatively movable in a linear direction during the burning of bristles.
50. In a machine for burning the ends of bristles, a support for the bristles, a coil of wire, a cylinder of non-conducting material for supporting the coil of wire, a shaft supporting the cylinder, means for rotating the shaft, contact rings mounted on the shaft and connected to the coil of wire, and contact brushes one for each contact ring on the shaft, said contact brushes being in a circuit for supplying electricity to the coil of wire, the support for the bristles and the coil of wire being relatively movable in a linear direction during the burning of bristles.
55. In a machine for burning the ends of bristles, a support for the bristles, a member arranged to be electrically heated, means for rotatably supporting the heated member, an electric motor for rotating the member, electrical connections to the motor and to the member, and a single switch for controlling said electrical connections, the support for the brush and the heated member being relatively movable in a linear direction during the burning of bristles.
60. In a machine for burning the ends of bristles, a support for the brush, an electrically heated wire, means for supporting the wire for contact with the bristles, means for rotating the wire to present constantly fresh surfaces for contact with the bristles, and means for causing relative movement of the wire and the brush lengthwise of the latter for treating successively bristles on all portions thereof.
65. In a machine for burning the ends of bristles, a support for the brush, a rotatably mounted cylinder of material refractory with respect to heat, a coil of wire wound helically on the cylinder and mounted for movement relative to the brush, means for electrically heating the coil of wire, means for rotating the cylinder and the wire to present constantly fresh surfaces for contact with bristles of the brush, and means for moving the coil of wire lengthwise of the brush support for treating successively bristles on all portions of the brush on the support.
70. In a machine for burning the ends of bristles, a support for the brush, a member arranged to be heated, a shaft for supporting the member, a motor for rotating the shaft and the heated member supported thereby, a carriage for supporting the heated member and the motor, and means for moving the carriage so that the heated rotating member may contact with successive portions of a brush on the support.
75. A machine for imparting a predetermined contour to the operating surface of a brush comprising, brush supporting means, a heated element, means for relatively mov-

ing the brush and the heated element to singe the surface of the brush, and means for pre-determining the extent to which the surface of the brush is singed.

5 In testimony whereof I have signed my name to this specification.
